HARRY E. MCALLISTER, OF MARINERS HARBOR, STATEN ISLAND, NEW YORK

AUTOMATIC WINDOW SASH LOCK

Application filed May 19, 1930. Serial No. 453,610.

This invention relates to new and useful improvements in an automatic window sash lock.

The invention has for an object the provision of a device of the class mentioned, which is of simple durable construction, dependable in use and efficient in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary plan view of an inner and outer window sash provided with the automatic window lock.

Fig. 2 is a fragmentary vertical sectional view taken on the line 2-2 of Fig. 1.

Fig. 3 is an elevational view as though looking in the direction of the line 3-3 of Fig. 1.

Fig. 4 is a fragmentary horizontal sectional view taken on the line 4-4 of Fig. 3.

Fig. 5 is a view similar to Fig. 4, but illustrating a modified form.

The automatic window sash lock as shown in Figs. 1, 2 and 4, comprises a bracket 10 for attachment on an inner window sash 11, a cup 12 rotatively mounted on said bracket 10 for engaging and locking in one position with a catch 13 on an outer window sash 14, means for urging said cup to move into locked position, a catch 15 for holding the cup in unlocked position, a stem 16 swivelly mounted, means on said stem and catch to cause rotation of the stem upon closing of said window sashes 11 and 14, and adjustable to another condition to cause a smaller degree of rotation, means for rotating said stem 16 back to initial condition upon opening of the sashes 11 and 14, and means operated upon full rotation of said stem 16 to trip the catch 15 and move it out of tripped position to allow resetting of the catch and upon slight rota-

tion to trip said catch and keep the catch in the tripped position.

The bracket 10 is provided with side lugs 17 and screws 18 engage through these lugs and into the window sash 11 for accomplishing the attachment on the sash. The bracket 10 is also provided with a central raised portion 19 so as to provide a space 20 between this portion and the sash 11. The cup 12 is formed with a flat base 21 resting upon the raised central portion 19 and with an inclined rim 22 for engaging said catch 13. The cup 12 is rotatable upon a bushing 23 attached on the top of the raised portion 19. A handle 24 projects from one side of the cup 12 for manual rotation whenever desired. The catch 13 is formed with a beak portion 25 adapted for engaging over the inclined rim 22 upon rotation of the cup 12, and with lug portions 26 engaged by the screws 27 engaging in the sash 14 for accomplishing the attachment of the catch upon the sash.

The means for urging the cup 12 to move into locked position, that is, the position in which the rim 22 engages beneath the beak 25 consists of a flat spring 28 attached at one end upon the bushing 23 and at the other end upon the flange 22 and arranged so as to normally accomplish the rotation. As viewed in Fig. 1, the spring normally urges the cup 12 clockwise. The catch 15 for holding the cup in unlatched position consists of a cylinder 30 attached upon the flat base 21 of the cup and supporting a piston 31 normally urged downwards by a spring 32 acting between the top of the piston and a plug 33 threaded into the top of the cylinder. The piston 31 is provided with a stem 34 engaging through an aperture in the bottom of the cylinder and engageable through apertures in the base 21 of the cup and in the raised portion 19. When all of these apertures are aligned the stem engages through them and accomplishes the latching of the cup in the condition shown in Fig. 1. This condition is the unlatched one of the device. The stem 16 extends through the bushing 23 so that a portion is disposed

within the space 20 and another portion above the bushing 23.

The means on said stem and catch to cause rotation of the stem upon closing of the 5 sashes 11 and 14 and adjustable to another condition to cause a smaller degree of rotation consists of a cam 36 on said catch movably supported and adjustable into fixed positions by screw 37. The stem 16 is caused 10 to rotate by a projecting finger 39 from the stem 16 engaging against the cam. In front elevational view the cam 36 is arranged at an inclination as may be seen from an inspection of Fig. 3 so that as the sashes 11 and 15 14 are moved to their closed positions the finger 39 will strike against the inclined surface of the cam 36 and cause the stem 16 to rotate through a certain angular distance. This distance may be adjusted by changing 20 the inclination of the cam 36 as for example indicated by the dot and dash lines 40 in Fig. 3.

The means for rotating the stem 16 back into initial condition upon opening of the 25 sashes 11 and 14 consists of a pair of flat springs 41, tensioned against the enlarged square portions 16' of the stem 16 within the space 20. The means operated upon full rotation of said stem 16 to trip the catch 31 30 and move out of tripped position to allow resetting of the catch and upon slight rotation to trip said catch and remain in the tripped condition consists of a trip bell crank 42 pivotally mounted intermediate its 35 ends at 43 upon the raised portion 19 of the bracket 10 and so positioned that its front end 44 is in line with the aperture in the raised portion 19 which receives the stem 34 when the latch is in its operative position. 40 The rear end of the bell crank 42 is pivotally connected with a link 45 which is pivotally connected at its other end 46 upon a radial finger 47 attached upon the stem 16.

When the catch 15 is in its operative position, the finger 47 is to one side of a line drawn between the trip 42 and the center of the stem 16. This condition of the device is shown in full lines in Fig. 4. When the stem 16 is caused to rotate upon the closing 50 of the sashes 11 and 14 the finger 47 moves to a position indicated by dot and dash lines 48 so as to be on the line between the center of the stem 16 and the trip 42. Such motion causes the link 45 to be moved so as to move 55 the trip 42 to force the stem 34 upwards and free the catch so that the spring 28 is free to rotate the cup 12 into its latching position. Further rotation of the stem 16 causes the finger 47 to move to a position indicated 60 by the dot and dash lines 49 in Fig. 4 which is now to the other side of the line drawn between the trip 42 and the stem 16. The motion of the finger to this latter position is transmitted by the link 45 to move the 65 trip 42 back into its initial condition so that

the catch 15 may again assume its operative position.

For following the operation of the device it is best to first assume the cup 12 to be latched in its inoperative position. Upon closing of the window sashes the finger 39 acts against the inclined surface of the trip 36 so as to cause rotation of the stem 16. As the stem 16 turns the finger 47 moves so as to first cause the trip finger 42 to press the stem 34 upwards for releasing the catch 15 so that the spring 28 turns the cup 12 into its latched condition. The latched condition is the one in which the flange 22 engages beneath the beak 25. As the sashes 11 and 14 80 assume the completely closed condition, the stem 16 rotates slightly further so that the finger 47 assumes the position indicated by dot and dash lines 49 and the trip finger 42 is moved out from the aperture in the raised 85 portion 19.

The window sashes are now locked and if the party desires to unlatch the sashes he may do so by merely manually moving the cup 12 back into its initial condition so that the plunger 34 engages within the aperture in the raised portion 19. Now the window sashes are closed, but in unlatched position. In the event that the party using the device wishes to make it impossible for the cup 12 90 to maintain an unlatched position while the sashes 11 and 14 are closed, it is merely necessary to loosen the set screw 38 and adjust the position of the cam 36 so that when the finger 39 acts against the cam the stem 16 is 95 merely rotated from a position as indicated by the full lines in Fig. 4 to the position as indicated by the dot and dash lines 48 in Fig. 4. It will be noticed that the trip finger 42 then maintains its position within the 100 aperture in the raised portion 19 so that the catch 15 cannot assume an operative position.

In Fig. 5 another form of the invention has been disclosed which differs from the 110 form just described in that in the normal position of the stem 16, the finger 47 is as shown in Fig. 5, that is, it is in such a position that the link 45 is on a line extending from the trip 42 through the axis of the stem 115 16. The trip 42 is out of engagement and positioned directly beneath the stem 34 of the plunger 31. Another change is that the trip 42 is positioned directly reversed to the trip before described, that is, the rear end 120 of the trip which connects with the link 45 is towards the link, as may be seen from an inspection of Fig. 5. An inspection of Figs. 1 and 4 clearly points out that the rear end 125 of the trip 42 is remote from the finger 47 relative to the front end of the trip.

These slight changes change the mode of operation somewhat. When the window sash is closed, the stem 16 is rotated so that the finger 47 moves to the position indicated by 130

the dot and dash lines 49 in Fig. 5 so that the trip 42 moves upwards and trips the stem 34 permitting the spring 28 to move the cup 22 so as to latch against the catch 13. Then upon complete closing of the window, the finger 39 from the stem slips off the cam 36 so that the springs 41 may return the finger 47 back into its original position in which position the trip 42 is out of the aperture originally occupied by the stem 34. The window now is locked, but if the operator so wishes he may manually reopen the cup 22 so that the plunger 31 moves to its lowered position and the stem 34 reengages in the aperture in the portion 19 for holding the cup open. Now the window is completely closed but not locked.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. An automatic window sash lock, comprising a bracket for attachment on an inner window sash, a cup rotatively mounted in said bracket for engaging and locking in one position with a catch on an outer window sash, means for urging said cup to move into locked position, a latch for holding the cup in unlatched position, a stem swivelly mounted, means on said stem to cause rotation upon closing of said window sashes and adjustable to another condition to cause a smaller degree of rotation, means for rotating said stem back to initial condition upon opening of said sashes, and means operated upon full rotation of said stem to trip said latch and move out of tripped position to allow resetting of said latch and upon slight rotation to trip said latch and keep the latch in the tripped position.

2. An automatic window sash lock, comprising a bracket for attachment on an inner window sash, a cup rotatively mounted in said bracket for engaging and locking in one position with a catch on an outer window sash, means for urging said cup to move into locked position, a latch for holding the cup in unlatched position, a stem swivelly mounted, means on said stem to cause rotation upon closing of said window sashes and adjustable to another condition to cause a smaller degree of rotation, means for rotating said stem back to initial condition upon opening of said sashes, and means operated upon full rotation of said stem to trip said latch and move out of tripped position to allow resetting of said latch and upon slight rotation to trip said

latch and keep the latch in the tripped position, said means for urging said cup to move into locked position comprising a spring having one end attached on the cup and the other end to some stationary part. 79

3. An automatic window sash lock, comprising a bracket for attachment on an inner window sash, a cup rotatively mounted in said bracket for engaging and locking in one position with a catch on an outer window sash, means for urging said cup to move into locked position, a latch for holding the cup in unlatched position, a stem swivelly mounted, means on said stem to cause rotation upon closing of said window sashes and adjustable to another condition to cause a smaller degree of rotation, means for rotating said stem back to initial condition upon opening of said sashes, and means operated upon full rotation of said stem to trip said latch and move out of tripped position to allow resetting of said latch and upon slight rotation to trip said latch and keep the latch in the tripped position, said latch for holding the cup in unlatched position comprising a cylinder attached upon the cup and housing a piston edged downwards by a spring acting between the piston and a plug in said cylinder, and a stem connected with said piston and engageable through aligned apertures in said cup and said bracket. 85

4. An automatic window sash lock, comprising a bracket for attachment on an inner window sash, a cup rotatively mounted in said bracket for engaging and locking in one position with a catch on an outer window sash, means for urging said cup to move into locked position, a latch for holding the cup in unlatched position, a stem swivelly mounted, means on said stem to cause rotation upon closing of said window sashes and adjustable to another condition to cause a smaller degree of rotation, means for rotating said stem back to initial condition upon opening of said sashes, and means operated upon full rotation of said stem to trip said latch and move out of tripped position to allow resetting of said latch and upon slight rotation to trip said latch and keep the latch in the tripped position, a bushing being stationary attached upon said bracket, and said stem engaging through said bushing. 105

5. An automatic window sash lock, comprising a bracket for attachment on an inner window sash, a cup rotatively mounted in said bracket for engaging and locking in one position with a catch on an outer window sash, means for urging said cup to move into locked position, a latch for holding the cup in unlatched position, a stem swivelly mounted, means on said stem to cause rotation upon closing of said window sashes and adjustable to another condition 125

- to cause a smaller degree of rotation, means for rotating said stem back to initial condition upon opening of said sashes, and means operated upon full rotation of said stem to trip said latch and move out of tripped position to allow resetting of said latch and upon slight rotation to trip said latch and keep the latch in the tripped position, a bushing being stationary attached upon said bracket, and said stem engaging through said bushing, and said means for urging the cup to move into locked position comprising a stem attached at one end on said bushing and at the other end of said cup.
6. An automatic window sash lock, comprising a bracket for attachment on an inner window sash, a cup rotatively mounted in said bracket for engaging and locking in one position with a catch on an outer window sash, means for urging said cup to move into locked position, a latch for holding the cup in unlatched position, a stem swivelly mounted, means on said stem to cause rotation upon closing of said window sashes and adjustable to another condition to cause a smaller degree of rotation, means for rotating said stem back to initial condition upon opening of said sashes, and means operated upon full rotation of said stem to trip said latch and move out of tripped position to allow resetting of said latch and upon slight rotation to trip said latch and keep the latch in the tripped position, comprising a trip bell crank pivotally mounted intermediate of its ends and arranged so that its front end is engageable for releasing said latch, a link connected with the rear end of said trip bell crank, and a radial finger fixed on said stem and connected with said link so that in normal position said radial finger is located to one side of a line extended between said trip and said stem and upon rotation of the stem to assume a position on said line or to the other side of said line.
7. An automatic window sash lock, comprising a bracket for attachment on an inner window sash, a cup rotatively mounted in said bracket for engaging and locking in one position with a catch on an outer window sash, means for urging said cup to move into locked position, a latch for holding the cup in unlatched position, a stem swivelly mounted, means on said stem to cause rotation upon closing of said window sashes and adjustable to another condition to cause a smaller degree of rotation, means for rotating said stem back to initial condition upon opening of said sashes, and means operated upon full rotation of said stem to trip said latch and move out of tripped position to allow resetting of said latch and upon slight rotation to trip said latch and keep the latch in the tripped position, the means on said stem to cause rotation comprising a cam adjustably mounted upon said stem and engageable by a finger projecting from the catch on said outer window sash.
8. An automatic window sash lock, comprising a bracket for attachment on an inner window sash, a cup rotatively mounted in said bracket for engaging and locking in one position with a catch on an outer window sash, means for urging said cup to move into locked position, a latch for holding the cup in unlatched position, a stem swivelly mounted, means on said stem to cause rotation upon closing of said window sashes and adjustable to another condition to cause a smaller degree of rotation, means for rotating said stem back to initial condition upon opening of said sashes, and means operated upon full rotation of said stem to trip said latch and move out of tripped position to allow resetting of said latch and upon slight rotation to trip said latch and keep the latch in the tripped position, said means for rotating said stem back into initial condition upon opening of said sashes comprising a spring acting between said stem and some stationary part.
9. An automatic window sash lock, comprising a bracket for attachment on an inner window sash, a cup rotatively mounted in said bracket for engaging and locking in one position with a catch on an outer
